ATTORNEY

INVENTOR

UNITED STATES PATENT OFFICE.

CLARENCE E. DRAKE, OF UNION, NEW YORK.

DOOR-HOLDER.

1,241,099.

Specification of Letters Patent. Patented Sept. 25, 1917.

Application filed March 30, 1916. Serial No. 87,822.

To all whom it may concern:

Be it known that I, CLARENCE E. DRAKE, a citizen of the United States, residing at Union, in the county of Broome and State of New York, have invented certain new and useful Improvements in Door-Holders, of which the following is a specification.

My invention relates particularly to a device adapted to hold a door in an open position after it has once been opened. It is particularly adapted for use in factories and the like where fire-doors are employed so that once a fire-door is opened, it cannot be again closed accidentally but the means of my invention must be released manually to permit closing of the door. It often happens that in fires in factories, the fire-doors become closed accidentally and thus prevent the escape of the occupants of the building due to the fact that, the panic arising as a result of the fire, persons entrapped are unable to open the door and maintain it in an open position. It is the prime object therefore, to provide a device which will eliminate this difficulty.

Another object of the present invention is to provide a device of the character set forth which is simple in construction, comprises a minimum number of parts, and is efficient in use.

With the above and other objects in view, I will proceed to describe one specific embodiment of the present invention with reference to the accompanying drawings where-35 in such embodiment is illustrated and which forms a part of the present specification.

In the drawings:

Figure 1 is a side elevation of a portion of a door of the sliding type equipped with a device embodying my invention.

Fig. 2 is a view similar to Fig. 1 but showing the door in open position, and

Fig. 3 is a sectional view on the line 3—3 of Fig. 2.

In detail:

The device as shown is applied to a door A having a casement or frame B. The door is of any suitable sliding type, or it may be of the swinging type, and the device itself 50 comprises a toggle indicated at C.

The toggle comprises two arms 1 and 2, the end of one being pivoted intermediate the ends of the other as shown at 3. One end of the toggle C is pivoted to the door end of frame B as shown at 4 whereas the other 55 end is pivoted to the door A as shown at 5

and thus as the door A is moved to the open position, the toggle members 1 and 2 will be pulled out into alinement with each other. It is to be noted that, due to the fact 60 that the arm 2 is pivoted intermediate the ends of the arm 1, a free end 6 is provided on the arm 1 and this end carries two lips 7 and 8 which are bent or offset with respect to the main portion to provide a clip which 65 will engage the arm 2 as the toggle is straightened out and thus will, when the door is in the position shown in Fig. 2 and the toggle arms in alinement, prevent said arms from buckling with respect to each 70 other with the result that any push or force applied to the door with the intention of closing it will not act successfully due to the fact that a straight, rigid arm or member formed by the toggle arms coming into 75 alinement will resist such closing effort and maintain the door in an open position.

Attached to the portion 6 of the arm 1 is an eye 9 carrying a chain 10 provided with a finger ring 11 and when the toggle is 80 straightened out as shown in Fig. 3, a slight pull on the finger ring 11 will be sufficient to cause the toggle to buckle and permit the door to close.

While, in the foregoing, I have described 85 and illustrated a specific embodiment of the present invention, it is nevertheless to be understood that, in practice, I may resort to such practical modifications as fall within the scope of the invention as defined in the 90 appended claims. And I may apply the device to swinging doors or windows or sliding doors and windows, without departing from the spirit of the invention.

I claim:

1. The combination with a door and frame, of a toggle connecting the said door and frame, one link of said toggle being longer than the other and the shorter link being pivoted to the longer link inwardly 100 from the outer end thereof, and lips projecting laterally from the longitudinal edges of one of said links for engagement with the corresponding edges of the opposing link when said links are alined.

2. The combination with a door and frame, of a toggle connecting the said door and frame, one link of said toggle being longer than the other, and the shorter link being pivoted to the longer link inwardly 110 from the outer end thereof, lips projecting from the longitudinal edges of said longer

link at the free end thereof, said lips being bent inwardly out of the plane of said longer link and then being flared outwardly, and a chain connected to the said free end 5 of said longer link.

3. The combination with a sliding door and frame, of a toggle link having one end pivoted to the door frame and the other end pivoted to the door, said toggle being 10 arranged to straighten out as the door is moved to the open position, lips carried by one part of the toggle for engagement with

the other part thereof when the toggle parts are in alinement to prevent the toggle from breaking and thereby hold the door in an 15 open position, and means for manually bending said toggle to permit closing of the door.

In testimony whereof I affix my signature in presence of two witnesses.

CLARENCE E. DRAKE.
